(57) **CLAIM**

The ornamental design for an edge retainer for a printed circuit card, as shown and described.

DESCRIPTION

FIG. 1 is a top, front, left-side perspective view of an edge retainer for a printed circuit card showing my new design; FIG. 2 is a bottom, front, left-side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a top, front, left-side perspective view of the edge retainer without the printed circuit card; and, FIG. 10 is a top, rear, left-side perspective view of the edge retainer without the printed circuit card. The broken lines in the drawing views are included to illustrate environment only and form no part of the claimed design.

1 Claim, 7 Drawing Sheets
